UNITED STATES PATENT OFFICE.

RHUEL B. HIBBARD, OF GROTON, NEW YORK, ASSIGNOR TO AIRDY CORPORATION, OF GROTON, NEW YORK, A CORPORATION OF NEW YORK.

DESIGN FOR A LAVATORY FIXTURE.

60,659.

Specification for Design. Patented Mar. 21, 1922.

Application filed June 7, 1921. Serial No. 475,725. Term of patent 14 years.

To all whom it may concern:

Be it known that I, RHUEL B. HIBBARD, a citizen of the United States, and resident of Groton, in the county of Tompkins and State of New York, have invented a new, original, and ornamental Design for Lavatory Fixtures, of which the following is a specification, reference being had to the accompanying drawing, forming a part hereof.

In the drawing, Fig. 1 is a front elevation; and

Fig. 2 a side elevation.

I claim:

The ornamental design for a lavatory fixture, as shown.

RHUEL B. HIBBARD.

Witnesses:

LE ROY C. BOWMAN,
J. G. BASSETTE.
